CLAIM

The ornamental design for a buffing pad, as shown and described.

DESCRIPTION

FIG. 1 is a perspective view of a buffing pad according to the invention.

FIG. 2 is a top view of the buffing pad shown in FIG. 1; and, FIG. 3 is side view of the buffing pad shown in FIG. 1.

The bottom of the buffing pad is not shown because it forms no part of the claimed design. The broken line showing at the center of the buffing pad in the FIGS. 1 and 2 views is for illustrative purposes only and forms no part of the claimed design.

1 Claim, 2 Drawing Sheets

FIG. 1

FIG. 2

FIG. 3
